UNITED STATES PATENT OFFICE.

ARTHUR R. BOXALL, OF ROME, NEW YORK.

DOOR-OPERATING MECHANISM.

1,238,740.

Specification of Letters Patent. Patented Sept. 4, 1917.

Application filed October 18, 1916. Serial No. 126,420.

To all whom it may concern:

Be it known that I, ARTHUR R. BOXALL, a citizen of Great Britain, residing at Rome, in the county of Oneida and State of New York, have invented certain new and useful Improvements in Door-Operating Mechanism, of which the following is a specification, reference being had therein to the accompanying drawing.

10 My invention relates to door operating mechanism, and I declare the following to be a full, clear, concise and exact description thereof sufficient to enable anyone skilled in the art to which it appertains to 15 make and use the same reference being had to the accompanying drawings in which like reference characters refer to like parts throughout the specification.

The object of the invention is to provide 20 a simple efficient device for opening and closing the doors of automobiles, carriages and other vehicles. Such a device will be found particularly valuable in connection with conveyances used for commercial purposes, such 25 as taxicabs and jitney busses. Furthermore, by the employment of this device the chauffeur is able to open or close the doors by actuating pedals located near his seat.

The object will be understood by referring 30 to the drawings in which:

Figure 1 is a perspective view of that part of the device which is disposed under the front seat of the automobile;

Fig. 2 is a perspective detail view of a bell 35 crank lever employed;

Fig. 3 is a plan view of the device, showing one door open and the other in closed position;

Fig. 4 is an enlarged detail view, showing 40 a perspective of the mechanism within the door for operating the latch;

Fig. 5 is an enlarged detail view, showing a perspective of certain arms employed for closing the doors;

Fig. 6 is a detail view in fragment, showing 45 a shaft and immediate parts for actuating the latch of the door, parts being illustrated in section;

Fig. 7 is an enlarged perspective view of 50 the hinges and immediate parts, employed;

Fig. 8 is an enlarged fragmentary view of the arms and shaft for closing the doors, certain parts being shown in section, and the view being taken from the rear, in order to

show the bevel sides of the heads of certain 55 plungers employed;

Fig. 9 is a perspective miniature view of a frame employed;

Fig. 10 is an enlarged perspective view of a ball and socket joint employed, the ball 60 being separated from the socket.

Referring more particularly to the drawings, the frame —1—, preferably disposed under the front seat of the automobile, is provided with the rock shafts 2 and 3. The 65 rock shaft 2 is supported in the bearings 4—4, as is shaft 3, and has fixedly mounted upon one end an arm 5. The free end of the arm 5 is attached at 6 to a connecting rod 7. The opposite end of the rod 7 is bifurcated at 8 and joined to the end of the bell crank lever 9 fulcrumed upon the rod 10 rigidly held in the standards 11—11, that may be suspended from the frame —1—.

The end of the rock shaft 2 opposite that 75 in which the arm 5 is attached has mounted to turn therewith an arm 15, connected by a ball and socket joint 12, as shown in Fig. 10, to a rod 16 whose other end is similarly united to the lever 17 fulcrumed at 18 upon a 80 fixed pivot mounted in the frame 19 of the automobile, which frame is recessed for the reception of the lever 17.

The free end of the lever 17 lies adjacent and is adapted to make contact with the end 85 20 of the lever 21 pivoted at 22 to a bracket 23 mounted in a suitable manner within the frame of the door of the automobile. The opposite end of the lever 21 is pivoted to a connecting link 24 that is in turn pivoted to 90 the end of a bell crank lever 25 fulcrumed at 26 to a bar 27 secured by its ends 28 within the door frame of the automobile.

The other end of the bell crank lever 25 is attached to an arm 29 by a connecting rod 95 30, ball and socket joints 12 being employed. The arm 29 is mounted to turn with the shaft 31 having a loose bearing in the disk 32 attached to the bracket 33 fixed to the bar 27. The upper end of the shaft 31 has a loose bearing in the lock 34 and is provided with a laterally projecting nub 35 whose free end fits within an elongated recess 36 formed in the latch 37 confined to a given sliding position within the lock 34 by the 105 guide members 38—38. A spring 39 attached to a block 40 normally presses against the inner end of the latch 37, whereby to

press said latch outward to engage the usual socket, not here shown, in the door frame, to lock the door.

A coiled spring 45 is attached to the free end of the arm 15 and to the rock shaft 46 by a ring 125, whereby to hold the arm 15 normally in the position illustrated in Fig. 1, after the operator has withdrawn his foot from the pedal 47 which is pivotally attached at 98 to the bell crank lever 9, so as to restore said pedal 47 and immediate parts to normal position.

The pedal 47 and likewise the pedal 50 will be held in upright position by suitable recesses formed in the floor of the automobile.

Inasmuch, as the latch 37 of the opposite door 51 is actuated in a similar manner to that of the door 60, just described, through the pedal 50, bell crank lever 52, rod 53, arm 54 fixedly mounted to rotate with the rock shaft 3, arm 55, rod 56 and a lever 17 with its accompanying train of levers and arm, as illustrated in Fig. 3 and heretofore described with reference to the door 60, it is not thought necessary to enlarge thereupon. A coiled spring 61 connecting the arm 55 to the shaft 46 by a ring 125 of the door 51, holds the pedal 50 and immediate parts in normal position.

The door 60, which is mounted to swing in the same manner as door 51, is supported by two hinges 62 and 63. The upper hinge 62 has a straight portion bent at 64 to form a cylinder adapted to embrace the stud 65 depending from the bracket 66 secured to the frame 19 adjacent the door of the car.

The lower hinge 63 has a straight portion projecting through a recess at 67 in the shaft 46. The reduced ends of the shaft 46 are mounted in loose bearings formed in the bracket 69 secured to the frame 19 and to the bracket 70 secured to the chassis of the automobile. The shaft 46 is rotated on its bearings by an arm 71 mounted to turn therewith and attached at its free end by a ball and socket joint 12 to a connecting rod 72 similarly united to a bell crank lever 73 fulcrumed upon a pivot mounted to the frame —1—. The bell crank lever 73 is joined to the bell crank lever 74 by a rod 75, the joints 12 being employed. The other end of the lever 74 is connected by a joint 12 to the rod 76 which is pivoted to the upper end of the arm 77 by a joint 12. The lower end of the arm 77 has formed integral therewith a sleeve 78 that is mounted upon a shaft 79 having bearings in the depending brackets 80—80 attached to the posts 104 of the frame —1—.

The shaft 79 is enlarged at 81 and provided with the rectangular shaped recesses 82—82 adapted for the disposition of the plungers 83—83. The upper ends of the plungers 83 are enlarged and rectangular in

cross section, whereby to prevent said plungers from turning within the recesses 82. One edge of the rectangular portion of the heads, is beveled off, in each instance, whereby to ride under the plunger 84 when 70 in its lower position and the shaft 79 is turned in a given direction.

The plungers 83 are held in normal elevated position by the springs 85 and pins 86 that limit the upward movement of the 75 plungers 83.

Each of the plungers 84 is slidably mounted in the upper block 90 and lower block 91, which blocks are attached to the arm 77. The lower end of each of the 80 plungers 84 is square in cross section, as at 92 adapted to be slidably mounted in a correspondingly shaped recess of the block 91. Said plunger 84 is held elevated in normal position by a coiled spring 93 which rests 85 against a pin 94 passing through said plunger 84. The shoulder formed by the lower rectangular portion of the plunger 84, limits the upward movement thereof.

Each of the plungers 84 is forced down 90 into engagement with the plungers 83 by a cam 95 fulcrumed at 96 to the arm 77. The cam 95 is rotated on its fulcrum 96, whereby to depress the plunger 84 by a rod 100 that connects said cam at 101 to the outer end of 95 the bell crank lever 74 by ball and socket joints 12. The depression of the plungers 84 by the cams 95 will dispose the lower ends of the plungers 84 in the path of the plungers 83, whereby the revolving of the 100 shaft 79 will cause the arms 77 to turn therewith to effect a resultant movement of the levers for closing the doors 51 and 60. Immediately the doors 51 and 60 reach closed position, the cams 95 will be actuated 105 automatically to their opposite position of that shown in Fig. 5 to effect a release of the mechanism tending to turn the arms 77.

The arm 77 is rocked upon its fulcrum, the shaft 79; whereby to effect a resultant actuation of the levers 74, 73, arm 71 and their connected parts to close the door 60 by the rotation of the shaft 79. The shaft 79 is rotated by an arm 110 mounted to turn therewith. The free end of the arm 110 is 115 attached by a ball and socket joint 12 to a rod 111, joined to the depending arm 112 integral with the sleeve 113 mounted to turn with the clutch shaft 114 which is rocked by the clutch pedal 115. The pedal 115 has an elbow 116 which forms also an integral part of the sleeve 113, whereby a downward push upon the clutch pedal 115 will rock the arm 112 and effect a similar movement of the arm 110 through the rod 111.

A coiled spring 103 connects one end of the bell crank lever 74 with the frame —1— adjacent the post 104, in order to hold the bell crank levers 74 and 73, and arm 71, in such position to normally force the door 60 130

into open position immediately the latch 37 is withdrawn from its locking recess, not shown.

The mechanism just described for closing the door 60 is duplicated with respect to the door 51, there being an arm 77, a plunger 84 adapted to contact with a plunger 83, a cam 95, a rod 100 connecting the cam with a lever 74, a rod 76 connecting the arm 77 with the lever 74, a bell crank lever 73 connected to the lever 74 by a rod 75, an arm 71 connected to the lever 73 by a rod 72, a rock shaft 46 and hinges 62 and 63. A spring 115 performs the same function with respect to this last named set of levers, as the spring 103 of the former set, namely to urge the door 51 into open position.

The operation of the device for opening the doors is effected by pressing with the foot upon one of the pedals 47 or 50 in accordance with the door to be opened. The depression of either pedal, as 47 causes a rocking of the bell crank lever 9 and a consequent movement of the rod 7, arm 5, rock shaft 2, arm 15, rod 16 and lever 17. The lever 17 will effect a movement of the mechanism located within the door frame, as illustrated more particularly in Fig. 3, by pressing downward upon the end 20 of the lever 21 to thereby actuate the link 24, bell crank lever 25, rod 30 and arm 29 with a resultant rotation of the shaft 31. This rotation of the shaft 31 will pull, through the nub 35, the latch 37 within the lock 34, against the tension of the spring 39 and away from the recess in the adjacent frame of the automobile, not shown.

The latch 37, being withdrawn, the spring 103 will exert a tension indirectly through the lever 73, rod 72 and arm 71 to force the door 60 into open position.

Immediately the foot is withdrawn from the pedal 47, the coil spring 45 will effect a return movement thereof, intermediately through the arm 15, shaft 2, arm 5, rod 7, and bell crank lever 9. Likewise, the lever 17 will be restored to normal position through the movement of the arm 15 and the rod 16, whereby to release the pressure on the end 20 of the lever 21 and thereby permit the projection of the latch 37 to return to normal position under the influence of the spring 39.

When the doors 51 and 60 are in open position, the cams 95 are automatically turned upon their fulcrums 96, whereby to depress the plungers 84 to lie opposite the plungers 83, by means of the connection of said cams 95 with the outer ends of the bell crank levers 74, through the rods 100. If either door 51 or 60 is opened the turning of the arm 110 and rock shaft 79, by depressing the pedal 115, will cause the plunger 83 now in contact with the plunger 84, to revolve the arm 77 upon the shaft 79

as a fulcrum and thereby effect a resultant movement of the levers 74, 73, arm 71, through their connections, and the rock shaft 46 to close the door.

As the door reaches closed position, the cam 95 will be revolved to the position illustrated in Fig. 5, so as to permit the plunger 84 to rise under the influence of the spring 93 and away from contact with the plunger 83, to effect a release of strain upon the levers and arm for closing the door.

In the event that either plunger 83 passes its corresponding plunger 84 and thereby renders the same ineffective for actuating the arm 77 to close the doors 51 or 60, the beveled surface of the head of the plunger 83 will permit the same to pass to the correct side of the plunger 84.

It will be noted that the arms of the bell crank levers 73 vary in length with respect to the arms of the bell crank levers 74. This variance is arranged progressively, whereby a small movement of the pedal 115 will transmit a greater movement of the arm 71 to close the door.

The shafts 2 and 3, are prevented from moving longitudinally with respect to their bearings 4 by the collars 120 held in place by set screws. Likewise, the sleeves 78 of the arms 77 are held in given position upon the shaft 79 by the collars 120.

Handles 121 are provided to work the latches 37 manually, if so desired.

Having thus described my invention, what I claim as new and desire to secure by Letters Patent is:

1. In a door operating mechanism, a door, means for opening said door, a door closing shaft, means for rotating said shaft, an arm loosely mounted on said shaft, means connecting said arm to the door, means on said arm for connecting it to the shaft, and means operated by the door connection when the door is nearing opened position to actuate the last named means to connect the arm to the shaft, whereby to close the door.

2. In a door operating mechanism, a door, means for opening said door, a door closing shaft, means for rotating said shaft, an arm loosely mounted on said shaft, means connecting said arm to the door, a plunger on said arm, and means operated by the door connection when the door is nearing opened position to actuate the plunger to connect the arm to the shaft, whereby to close the door.

3. In a door operating mechanism, a door, means for opening the door, a door closing shaft, means for rotating it, an arm loosely mounted on said shaft, means connecting said arm to the door, a plunger on said arm, means operated by the door connection when the door is nearing opened position to operate the plunger to connect the arm to the shaft and means for disconnecting the

plunger from the shaft when the door is closed. the door is nearing opened position to operate the plunger to connect the arm to the shaft and means for disconnecting the plunger from the shaft when the door is closed.

4. In a door operating mechanism, a door, means for opening the door, a door closing shaft, means for rotating it, an arm loosely mounted on said shaft, means connecting said arm to the door, a plunger on said arm, a cam operated by the door connection when
5. In testimony whereof I have affixed my signature.

ARTHUR R. BOXALL.
